UNITED STATES PATENT OFFICE.

HANS FRIESS, OF BERLIN-WILMERSDORF, GERMANY, ASSIGNOR TO ASKANIA-WERKE
A.-G. VORMALS CENTRALWERKSTATT DESSAU UND CARL BAMBERG-FRIEDENAU,
OF BERLIN-FRIEDENAU, GERMANY, A CORPORATION OF GERMANY.

CINEMATOGRAPHIC EXPOSING APPARATUS.

Application filed November 16, 1926, Serial No. 148,706, and in Germany November 17, 1925.

This invention relates to a cinematographic exposing apparatus which is distinguished primarily by the two features that, firstly, its film holders are arranged side by side, 5 and secondly, its front portion can be opened upwardly. It is already known to provide cinematographic exposing apparatus with a plurality of objectives adapted to be used alternately and arranged in a rotatory head, 10 but the arrangement and combination of the parts in said apparatus as designed up to now has been such that the film holders could be arranged either only one behind the other or one above the other, the film being in either 15 case conducted in a straight line from the one holder across the objective to the other holder.

It is with such devices, when the film holders are arranged side by side, difficult to 20 house the upper film loop in a suitable manner because that place at which the loop forms is occupied already by the rotatory objective carrier. The first part of the present invention relates to providing a suitable space 25 for that loop, and for this purpose I have provided a separate space behind the rotatory carrier at the top of the apparatus by arranging the front portion of the top plate of the apparatus on a higher plane, and 30 also the adjacent portion which is hinged to that raised top portion rises up to it whereby said separate space for the film loop mentioned is obtained.

Another part of this invention consists in 35 the feature that the rotatory objective carrier is located completely within the projection apparatus, or is, in other words, surrounded on all sides with a protective casing whereby it is prevented completely from being damaged.

Finally, the space in which the rotatory objective carrier is housed may also be closed by a cover, having an opening arranged coaxially with that objective which is in its 40 working position and to this cover may be fastened a separate tube ring located coaxially with that objective which is in its working position; that tube ring is intended for attaching to it, for certain extraordinary

purposes, a separate optical device or member, for instance such a one as employed in tele-optics, or an additional diaphragm, or the like.

The invention is illustrated diagrammatically and by way of example on the accompanying drawing, on which

Fig. 1 is a longitudinal section through a cinematographic exposing apparatus designed according to this invention, and

Fig. 2 is chiefly a plan and partly a horizontal section of the same.

On the drawing, *a* denotes the main box proper of the apparatus, *b* its front portion which can be opened upwardly, and *c* hinges connecting *a* and *b* with each other. The 65 rotatory head *d* which carries a plurality of objectives *e* is housed in the portion *b*. That objective which is in its lowermost position at the time being is in its working position opposite the film *i*. The rotatory head is turnable 70 upon the pivot *g* and can be fixed in its adjusted position by any suitable means (not shown in the drawing). In the main box *a* are arranged side by side a winding-off film holder *p*¹ and a winding-on film-holder *o*¹. 75 The film strip *i* leaving the holder *p*¹ passes over a sprocket wheel *h*, forms then a loop *k*¹, and proceeds now downwardly across the objective opening *f*; the film, after having been exposed forms another loop *p* passes over another sprocket wheel *q*, and disappears finally in the holder *o*¹. To render possible the formation of the loop *k*¹ without 80 colliding with the uppermost objective which is not in its working position, the box portions *a* and *b* are enlarged upwardly in the manner shown in Fig. 1, that is to say, while in the old constructions the plane *m* is the bordering plane of the entire top surface of 85 the apparatus, the top plane of the portion *b* of the apparatus is now higher and the two top portions of *a* and *b* are connected with each other by an oblique wall portion *n*; in front of the portion *b* and below the higher top portion is a chamber *k* enclosing the film 90 loop *k*¹ which is, therefore, not in the least disturbed by the rotatory head *d*, or by the objectives *e* respectively.

Finally, the space in which the rotatory objective carrier is housed may also be closed by a cover, having an opening arranged coaxially with that objective which is in its working position and to this cover may be fastened a separate tube ring located coaxially with that objective which is in its working position; that tube ring is intended for attaching to it, for certain extraordinary 95

Adjusting the device into working position may be effected in various ways, for instance by hand.

There is provided also a device for adjusting the distance, this device consisting of a lever *s* affixed firmly to an axle *t* inserted into a hollow pivot *g* and carrying a pin *u* engaging a groove *v* provided at the inner side of the bore of the pivot *g*. A screw *w* screwed 10 into the hollow pivot *g* from the front end of this latter holds all these parts together. If the lever *s* is turned in one or the other direction the pin *u* is moved along in the curved groove *v* whereby the pivot *g*, together with 15 the rotatory objective carrier, is shifted axially to the one or the other side.

This adjustment serves for regulating the distance. The graduated scale *x* pertaining to the lever *s* is of tubular shape so that that 20 portion which pertains to the objective that is in its working position at the time being, can be exposed to view.

As appears from the drawing, the rotatory objective carrier is located completely 25 within a casing. This casing may be formed for instance by a chamber *y* of the camera, the walls of which enclose the respective objective on all sides. Said chamber *y* is, preferably, closed by a cover *z* affixed to the 30 casing by screws *z*¹ and leaving an opening solely at that place where the just employed objective is located.

It is suited to the purpose in view to provide at said place a tube ring *T*, the thread-carrying extension of which extends through 35 said cover *z* and is affixed to it by a nut *T*¹. This tube ring is provided in known manner with an extension *T*² to which, if needed, a particular optical device or member such, 40 for instance, as employed for tele-optics, or an additional diaphragm, may be attached.

The arrangement and combination shown 45 may be modified in various ways without departing from the gist of the invention, the latter being applicable not only with cinematographic exposing apparatus in which the several objectives are located in a rotatory head or carrier, but also with such in which 50 this carrier is shiftable in a plane.

I claim:

1. In a cinematographic exposing apparatus, in combination, a main box of the camera, a separate front portion connected with said 55 box in such a manner as to be adapted to be opened pivotally and being enlarged relatively to the main box, a plurality of objectives arranged within said front portion, a common carrier for them, a winding-off film holder and a winding-on film holder arranged side by side within the main box, guide members for the film and an enlarged 60 portion arranged on the main box and forming with the said front portion a chamber 65 adapted to receive that portion of the film

loop which is located near said objective carrier.

2. In a cinematographic exposing apparatus, in combination, a main box of the camera, a separate front portion connected with said box in such a manner as to be adapted to be 70 opened pivotally, a plurality of objectives arranged within said front portion, a common carrier for them, a winding-off film holder and a winding-on film holder arranged side by side within the main box, guide members for the film and a chamber formed by a higher portion of the main box and front portion, an oblique wall portion 75 connecting the top walls of said main box and said higher portion with each other, said chamber being adapted to receive that portion of the film loop which is located near said objective carrier.

3. In a cinematographic exposing apparatus, in combination, a main box of the camera, a separate front portion connected with said box in such a manner as to be adapted to be 80 opened pivotally, a plurality of objectives arranged within said front portion, a common carrier for them, a winding-off film holder and a winding-on film holder arranged side by side within the main box, guide members for the film, a protective casing connected 85 with said front portion and enclosing said objectives and said carrier on all sides, a closure adapted to close said protective casing 90 at its front and having only an opening arranged coaxially with that objective which 95 is in its working position and a tube ring 100 affixed to and arranged over the opening of the closure and adapted to receive a special optical device.

4. In a cinematographic exposing apparatus, in combination, a main box of the camera, a separate front portion connected with said box in such a manner as to be adapted to be 105 opened pivotally and being enlarged relatively to the main box, a plurality of objectives arranged within said front portion, a common carrier for them, a winding-off film holder and a winding-on film holder arranged side by side within the main box, guide members for the film, an enlarged portion 110 arranged on the main box forming within the said front portion a chamber adapted to receive that portion of the film loop which 115 is located near said objective carrier, and a protective casing enclosing said objectives 120 and said carrier on all sides.

5. In a cinematographic exposing apparatus, in combination, a main box of the camera, a separate front portion connected with said box in such manner as to be adapted to be 125 opened pivotally and being enlarged relatively to the main box, a plurality of objectives arranged within said front portion, a common carrier for them, a winding-off film holder and a winding-on film holder arranged side by side within the main box, 130

guide members for the film, an enlarged portion arranged on the main box forming with said front portion a chamber adapted to receive that portion of the film loop which is located near said objective carrier, a protective casing enclosing said objectives and said carrier on all sides and means adapted to close said protective casing at its front and having only an opening arranged coaxially with that objective which is in its working 10 position.

In testimony whereof I have affixed my signature.

HANS FRIESS.
